(57) **CLAIM**

The ornamental design for a hand puppet, as shown and described.

DESCRIPTION

FIG. 1 is a top, front and side perspective view of a hand puppet showing my new design;

FIG. 2 is an elevational view of the left side of the hand puppet of FIG. 1;

FIG. 3 is an elevational view of the right side of the hand puppet of FIG. 1;

FIG. 4 is an elevational view of the front side of the hand puppet of FIG. 1;

FIG. 5 is a top plan view of the hand puppet; and,

FIG. 6 is a rear elevation of the hand puppet.

The broken lines in the drawings are for illustrative purposes only and do not form part of the claimed design.
